(57) **CLAIM**

The ornamental design for an earphone with in-ear piece, as shown and described.

DESCRIPTION

FIG. 1 is a perspective view of an earphone with in-ear piece in accordance with my design;

FIG. 2 is a back elevation view of the earphone with in-ear piece in accordance with my design;

FIG. 3 is a front elevation view of the earphone with in-ear piece in accordance with my design;

FIG. 4 is a top view of the earphone with in-ear piece in accordance with my design;

FIG. 5 is a bottom view of the earphone with in-ear piece in accordance with my design;

FIG. 6 is a left side elevation view of the earphone with in-ear piece in accordance with my design; and,

FIG. 7 is a right side elevation view of the earphone with in-ear piece in accordance with my design.

The broken lines shown in the drawings depict portions of the earphone with in-ear piece that form no part of the claimed design.
